REDUCING MACHINE

Chester Arthur Harbert, Jennings, La.

Application August 17, 1935, Serial No. 36,725

1 Claim. (Cl. 128—33)

This invention relates to a reducing machine and has for an object to provide a means for reducing the weight of a person without the necessity of any undue exertion on the part of the person utilizing the same.

A further feature of this invention is that it may be made to fit persons of any weight or size and that the same machine may be used for reducing the weight of a more corpulent or a less corpulent person. As is well known, the stouter a person is the lazier he is and the harder he finds it to go through any systematic method of reducing his weight which calls for exertion on his own part. The fat or corpulent person, however, is often quite anxious and desirous to reduce but due to his very condition is often unable to indulge in sufficient exercise to cause the necessary loss of weight.

With this invention, however, no physical exertion is necessary on the part of the person who desires to lose weight. He need only place himself in the machine of this invention at regular periods and submit himself to the exercise performed on him by the machine until his weight has finally been reduced to the desired amount.

As a further feature of this invention, the person whose weight is being reduced is rolled back and forth about his length so that the greatest exercising effect is produced on those portions of the body which project the greatest distance which, in the case of a corpulent person, is usually under the belt line, thereby causing the belt line to be most effectively reduced.

With the foregoing and other objects in view, as will hereinafter become apparent, this invention comprises the constructions, combinations and arrangements of parts hereinafter set forth, disclosed and shown on the accompanying drawings. In these drawings:

Fig. 1 is a side elevational view of the invention.
Fig. 2 is a top plan view of Fig. 1.
Fig. 3 is an end view of the reducing machine, and
Fig. 4 is an enlarged sectional view taken on the line 4—4 of Fig. 2.

There is shown at 10 the reducing machine of this invention. This reducing machine comprises a hollow cylinder 11 having one end open as at 12. The other end of the cylinder 11 is closed as at 13 and extending from this closed end 13 and secured thereto as at 14 is a shaft 15 on which is keyed a gear 16. This shaft 15 extends to a bearing 17. The bearing 17 is located in a support 18 mounted in a base or frame 19, thereby supporting one end of the cylinder 11. The other end of

the cylinder 11 rests on a series of roller bearings 20 placed in an upstanding leg 21 at the end of the base or frame 19.

A motor 22, which may be electrically operated from any suitable source of power rests on an extension 23 of the base or frame 19 and operates a fly wheel 24 by means of an endless belt 25. A shaft 26 keyed to the fly wheel 24 is formed into a crank arm 27, its other end being journaled in a suitable bearing in a pedestal 28 formed in the frame 19, the shaft 26 being journaled in the pedestal 29. A connecting arm 30 is joined at one end thereof to crank arm 27 by means of a bearing or the like and at its other end is connected by a similar bearing to toothed rack 31. This rack 31 is supported on a U-shaped bed 32 secured to the support or leg 18, the bed 32 being so located as to cause the teeth of the rack 31 to remain enmeshed with the teeth of the gear 16.

As the motor 22 is operated, the crank arm 27, through its connecting rod 30, imparts a reciprocatory motion to the toothed rack 31 and thus causes the cylinder to reciprocate back and forth. Any desired amount of rotation can be provided by merely selecting the proper ratio between the crank arm and the gear, but preferably the ratio selected will be such as to cause the cylinder to rotate through slightly over 180 degrees before the reciprocatory motion is started.

In operation, the person desiring the exercising effects of this machine merely inserts his body through the open end 12 of the cylinder 11 and lies at full length therein. If desired, the inside of the cylinder 11 may be provided with a suitable padding or mattress to prevent bruising the person utilizing the same, although a switch or control for the motor 22 may be located adjacent the open end so that the person exercising himself therein may be able to discontinue the operation at the appropriate time.

The operation of the motor 22 will cause the person in the cylinder 11 to be rolled back and forth continuously so long as the motor is in operation, the rolling effect thereby exercising the person and causing a loss of reduction in his weight.

The novel features and the operation of this device will be apparent from the foregoing description. While the device has been shown and the structure described in detail, it is obvious that this is not to be considered limited to the exact form disclosed and that changes may be made therein within the scope of what is

claimed without departing from the spirit of the invention.

Having thus set forth and disclosed the nature of this invention, what is claimed is:

- 5 A reducing machine comprising a base, a hollow cylinder having one open face and one closed face, roller means carried by the base at one end thereof, said roller means supporting the hollow cylinder adjacent its open end, a shaft secured to the closed end of the cylinder, a bearing support for said shaft carried by the end

of the base opposite that carrying said roller means, means for reciprocating said shaft to reciprocate said cylinder about its longitudinal axis, said reciprocating means comprising a gear secured to the end of the shaft, a toothed rack meshing with said gear, a bed carried by said base supporting said rack, and a motor and crank connected to said rack for imparting a reciprocating motion thereto.

10
